UNITED STATES PATENT OFFICE.

GEORGES MICHEL SCHREIBER, OF CZENSTOCHOW, RUSSIA.

APPARATUS FOR PREVENTING COLLISIONS, &c., ON RAILWAYS.

SPECIFICATION forming part of Letters Patent No. 658,806, dated October 2, 1900.

Application filed May 17, 1899. Serial No. 717,169. (No model.)

To all whom it may concern:

Be it known that I, GEORGES MICHEL SCHREIBER, residing at Czenstochow, Government Pietrokoff, Theatralad, in the Empire of Russia, have invented certain new and useful Improvements in Apparatus for Preventing Collisions and other Accidents on Railways, (for which I have applied for patents in Germany dated March 25, 1899; in 5 Austria dated March 27, 1899; in Hungary, No. 4,609, dated March 28, 1899; in France, No. 275,256, dated March 29, 1899; in Belgium, No. 111,242, dated March 29, 1899; in Italy dated March 30, 1899; in Spain dated 10 March 30, 1899; in Portugal dated April 5, 1899; in Sweden, No. 570, dated March 29, 1899; in Norway, No. 10,979, dated March 29, 1899; in Denmark, No. 351, dated March 29, 1899, and in England, No. 6,848, dated March 15 20 30, 1899,) of which the following is a specification.

Many attempts have been made to construct apparatus to prevent the collision of trains and other accidents on railways, which, however, have been unsuccessful, the apparatus not fulfilling all the various requirements. Such apparatus was adapted only for the proximity of signal-boxes and stations, so that accidents could still happen on other 25 30 parts of the railway, and, further, the operation of such apparatus depended more or less upon the staff of the railway and was therefore subject to human error.

This invention relates to apparatus which 35 acts automatically and independently of the engine-driver and other staff and is designed to prevent collisions and other accidents at all parts of a railway. This object is obtained mainly by the distribution of devices 40 along the whole road, which are arranged one before and one behind the train, to be protected at a certain distance therefrom, so that another train can approach the first train only to a certain distance in front or behind 45 such train, because when the second train meets the devices it is automatically stopped by the action of the brake and interruption of the steam-supply.

In order that this invention may be the better understood, I now proceed to describe the same, reference being had to the accompany-

ings and to the letters and figures marked thereon.

Figure 1 is a diagrammatic view showing the general arrangement of the apparatus. 55 Fig. 2 shows a side and part sectional view of the protecting device arranged at certain intervals on the road. Fig. 3 shows similar views of this device at a different position of the working parts. Fig. 4 is a view in the 60 direction of the arrow, Fig. 2. Fig. 5 is a view from the other side in the direction of the arrow, Fig. 3. Fig. 6 is a plan of part of the device. Fig. 7 is a plan of the whole arrangement, and Figs. 8 to 14 show details explained in the following description. 65

Fig. 1 illustrates, as before mentioned, the general arrangement of the invention. For the sake of simplicity one line of rails is only assumed outside, to the right and left of 70 which are arranged in pairs the protecting devices 1 3 5 7, &c., and 2 4 6 8, &c. On one side are arranged the devices with uneven numbers and on the other side the devices with even numbers. To each of these devices correspond two adjustable striking devices within the rails, which when the corresponding protecting device is operated by a passing train occupy such a position that a lever provided under the locomotive strikes 75 80 85 against them and is operated, so as to actuate the pneumatic or steam brake, to interrupt the steam-supply, and, if desired, to give a visible or audible signal to the engine-driver, so that the blocked road cannot be passed over by a train in either direction except by the train which has automatically effected the blocking. 90

Suppose a train travels along the road in the direction of the arrow and is provided on the right side of the locomotive with a lever outside the rails adapted to strike against a lever of the devices 1 3 5 7, &c. Suppose also the train has traveled far enough to have passed device 5 and passes the device 7. 95 The operation of the device moves two blocks 7^a and 7^b, both connected with the device 7 by drawing mechanism, so that projections a of the blocks occupy the positions shown in dotted lines in Fig. 14. If now a driver intends to pass the blocks 7^a or 7^b thus adjusted, the lever b, suitably placed below the frame 100

of the locomotive, would strike against the projection α of the corresponding block, whereby an axle c will be rotated. (See Fig. 14, which illustrates as an example how this mechanism 5 may be constructed.) By means of a cord d or similar device the rotation of the axle c operates a catch e . A disk f makes then a rotary movement under the action of a weight. The rotation of the disk f actuates either the 10 brake of the train or interrupts the steam-supply to the cylinders, or both, and it may further give an audible or visible signal to the driver that the train must stop.

Referring now again to Fig. 1, when the 15 train passed device 7 the blocks 7^a and 7^b occupied such a position that this part of the road can now be passed over only by the train which passed device 7, being blocked from the rear and from the front against any other 20 train. The block 7^b while operated has acted on the device 3, previously operated by the same train, and has disengaged the same, so that the device 3 and blocks 3^a and 3^b have returned into the position previously 25 occupied by them. When the train travels farther and passes the device 9, the procedure is repeated, the blocks 9^a and 9^b are adjusted, and the device 5, previously actuated, with the blocks 5^a and 5^b , are returned into the 30 original position. It will be seen that the train is protected for a certain distance in front and rear and controls this part of the road for itself, blocking it against other trains and relieving the block when it has 35 advanced sufficiently far so as not to further require the protection. The following is a description of the details of such a device provided on the right and left of the line and covered conveniently by a box.

40 In a frame m , conveniently fixed outside the line, rests an axle h , Fig. 3. The axle h carries a lever g , provided with a pivoted end k . When a train approaches, the lever g is turned over by an arm fixed below the locomotive and turns a cog-wheel i in the direction of the travel. The cog-wheel i engages with a cog-wheel o , rigidly connected with a ratchet-wheel p , Figs. 2, 10, and 11. When the lever g was being turned over, a weight 45 l was wound up, which operates immediately after the passing of the lever g and rotates the cog-wheels i and o in opposite direction. Before the lever g is turned over by the arm under the locomotive the parts occupy the position shown in Fig. 8. A ratchet-pawl t , fixed to the cylinder s and subject to the influence of a spring x , engages with the teeth of the ratchet-wheel p , which rotates loosely with the wheel o around an axle r . When the lever 50 g is turned over and the wheels i and o are rotated, the ratchet-pawl t passes over the teeth of the ratchet-wheel p without effect. However, when the train has left the device and the wheels i and o are rotated by the falling 55 weight l —that is to say, in the direction opposite to that before—the ratchet-wheel p carries the pawl t with it, and as the same is fixed

to the cylinder s the latter is rotated in the same direction until the nose 31 of the same is engaged by a pawl 30 , and thus secures the cylinder s in the position given to it. The various parts then occupy the position shown in Fig. 9. The free end of the pawl t has been moved by the pin t' , so that the pawl is disengaged from the ratchet-wheel p . A lever z , 75 pivoted at w , is moved by the spring 15 , so that its lug v , entering through the orifice u of the ratchet-pawl, arrests the latter in its disengaged position. The spring x , which has the tendency to press the pawl t into the teeth 80 of the ratchet-wheel p , cannot come into effect. To the cylinder s are attached the ends of two chains 16 and 17 , so that the chains, which run along two different directions of the railway, are both wound up during the rotation of the cylinder s , due to the action of the weight. The chains lead to a block device situated in front or behind the train and marked 1^a 2^a 3^a , &c., and 1^b 2^b 3^b , &c., according to the main devices to which they belong. 85 (See Fig. 1.) The construction of these block devices is shown in Figs. 2 and 3. The apparatus consists, essentially, of a casing a , in which is rotated a cog-wheel 22 with an axle 32 , lifting a rack 20 and bringing it and the projection 21 into the position shown in Fig. 3. In this position of the projection the blocking of the line and projection of the train have been effected. As shown in Fig. 7, an axle 32 carries three chain or wire pulleys 33 , 34 , and 35 , of which 33 is connected with a chain or wire service led to the apparatus from which the block has been adjusted. The pulley 34 is connected to the nearest main device in order to free simultaneously with the lifting of the corresponding projection the part of the road which is not to be blocked any longer. The third pulley 35 carries a weight 23 in order to return the parts into their position of rest when the block in question has 90 been set free again, Fig. 2. 100

To the block device a (shown on the left in Fig. 7) belong two disks or pulleys 36 and 37 , of which 36 is connected to the main device, pulley 37 carrying the weight 23 to pull down 105 the projection 21 . The third pulley is omitted in this case, because only the block devices on the right side in the direction of the travel of the train are required to return the devices into the positions of rest. 115

When a main device is operated, the train can travel to and fro on the part of the railway blocked by it without disengaging the block or resistance from the parts. For instance, when the locomotive-arm has turned 120 over the lever g , Fig. 3, and the driver wishes to go back with the train—for instance, to fetch a disconnected carriage—the hinged end k is turned into the position shown in dotted lines and permits the train to pass. When 125 afterward the train travels again forward and turns the lever g over again, the cog-wheels i and o are operated and rotate the ratchet-wheel p ; but as the pawl t of the cylinder s is 130

pressed out of the teeth of the ratchet-wheel the wheel will simply turn without influencing the cylinder blocked in its position and the blocks or projections connected therewith.

5 As before mentioned, by means of the disk 34, Fig. 6, the nearest device is returned into the position of rest. For this purpose a line of wire or chain, connected to the pulley 34, is connected with a sliding device 24, Fig. 12, 10 and adjusts the same, overcoming a spring 25, Fig. 3. The projection of the slide 24 then passes against a pivoted arm of the lever 28, and thus brings the projection 30 in such a position that the projection 31 of the 15 disk becomes free, and the cylinder *s* can consequently return into its original position, whereby the corresponding block devices return into their position of rest. The lever 28 is shown in detail in Fig. 13 and is subject 20 to the pressure of a spring 29. The return of the cylinder *s* is effected by the weights 23 of the block devices. When the cylinder *s*, Fig. 15, returns, the end 19 of the lever *z* strikes against a projection 18, as shown in 25 Fig. 8. In consequence the projection *v* passes through the opening *u* of the ratchet-pawl *t*, overcoming the spring 15, whereby the ratchet-pawl *t* is brought again into engagement with the ratchet-wheel under the influence of the spring *x*. The parts then have 30 taken up the position ready for action, so that the procedure can be repeated.

In the following case the present invention is of special value. If, for example, it be supposed that two trains on the same line approach each other with such a velocity that a collision at some point on the line—as, for example, between 17 18 and 19 20—would take place, the train advancing from the right 40 upon passing the apparatus 15 would raise the block 15^a, which would force the train advancing from the left to stop. This latter train, since upon passing the apparatus 22 it actuates the block 22^a, will likewise prevent 45 the train coming from the right from farther advancing. It is consequently quite impossible with the subject-matter of the present invention that the distance between the apparatus 17 18, on the one hand, and 19 20, on 50 the other, where a collision could have hitherto taken place, be passed over by two trains approaching from opposite directions. The same effect would be produced if a train were 55 to run off the line at any point. In this case also the point in question would be completely protected.

In the following claims I use the expression "train-stopping device" to mean any means for automatically or indirectly causing 60 it to be stopped.

What I claim, and desire to secure by Letters Patent of the United States, is—

1. In combination in apparatus for preventing railway accidents, a series of train-stopping devices, a setting device consisting of a 65 train-operated lever and means for setting and resetting the same, and each connected

to set two of the said train-stopping devices at a distance in each direction along the track, and connections for resetting the said 70 train-stopping devices from a much greater distance along the track, whereby an engine or train will successively set the train-stopping devices at a given distance in advance and at a given distance in the rear, and subsequently reset them, substantially as set forth.

2. In combination in apparatus for preventing railway accidents, a series of train-stopping devices, a series of setting devices, said 80 devices consisting of a cylinder *s*, and lever and mechanism for setting and resetting the lever, all being situated without the line of rails therefor actuated by engines or trains when moving in one direction only, and each 85 connected to set two of the said train-stopping devices at a distance in each direction along the track, and connections for resetting the said train-stopping devices from a much greater distance along the track, whereby 90 by an engine or train will successively set the train-stopping devices at a given distance in advance and at a given distance in the rear, and subsequently reset them, substantially as set forth.

3. In combination in apparatus for preventing railway accidents, a series of train-stopping devices for engines or trains going in one direction, comprising a cylinder or drum and a train-operated lever with means for setting and resetting the same a series of train-stopping devices for engines or trains going only in the opposite direction, a series of setting devices therefor, operated only by engines or trains going in the first said direction and connected to set one of the train-stopping devices at a suitable distance ahead and one of them at a suitable distance in the rear, and means for resetting the said stopping devices to normal position when the engine or train has gone farther, substantially as set forth.

4. In combination in apparatus for preventing railway accidents, a series of train-stopping devices for engines or trains going in one direction, a series of train-stopping devices for engines or trains going only in the opposite direction, a series of setting devices therefor consisting of a cylinder and lever, operated only by engines or trains going in the first said direction and connected to set one of the train-stopping devices at a suitable distance ahead and one of them at a suitable distance in the rear, and means for resetting the said stopping devices to normal position when the engine or train has gone farther, a similar series of setting devices operated only by engines or trains going in the opposite direction on the same track, and two similar corresponding series of coöperating train-stopping devices and means for resetting them, whereby an engine or train will be protected against being run into by trains approaching it in either direction, and also

against running into a standing or derailed train, substantially as set forth.

5. In combination with a train-stopping device, a cylinder *s* at a distance operatively connected thereto, a train-operated lever, a weight acting upon the lever in direction to return it to normal position when actuated by a train, a pawl and ratchet and connections between said lever and said cylinder

10 for actuating the cylinder by the return move-

ment of the said lever, and means for resetting the cylinder to its normal position, substantially as set forth.

In testimony whereof I have hereunto set my hand in the presence of two witnesses. 15
